UNITED STATES PATENT OFFICE.

ARTHUR JAMES POSTANS, OF LEAMINGTON SPA, ENGLAND, ASSIGNOR TO W. J. MYATT & COMPANY LIMITED, OF BIRMINGHAM, ENGLAND.

RAZOR-STROPPING DEVICE.

Application filed October 27, 1924. Serial No. 746,158.

To all whom it may concern:

Be it known that I, ARTHUR JAMES Postans, a British subject, residing at 34 Leam Terrace, Leamington Spa, in the county of

5 Warwick, England, have invented certain new and useful Improvements Relating to Razor-Stropping Devices, of which the following is a specification.

This invention relates to razor stropping devices and particularly to safety razors or stropping devices therefor in which the blade holder is adapted to be swung from one position to another at the end of each stropping movement so that the opposite sides 15 of the blade are acted on alternately.

Experience proves that it is desirable, especially in the case of safety razor blades, to subject one side of the blade to a rather stronger stropping action than the other.

20 Apparently in the act of shaving, the edge of the blade is apt to be turned back in the direction away from the guard, and a condition in satisfactory stropping is that this effect shall be counteracted.

25 The present invention comprises the adaptation of the stropping mechanism to cause greater pressure to be exerted between the blade and stropping surface in one stroke than in the next.

30 In particular the invention comprises the employment of eccentric toothed pinions, or eccentric roller or other mechanism for imparting the successive swinging movements to the blade holder.

35 In the accompanying sheet of explanatory drawings:

Figure 1 is a side elevation, and Figure 2 a front elevation showing one application of the invention to a safety razor.

40 Figures 3 and 4 are diagrams illustrating the action of the stropping mechanism.

In one well known form of safety razor (illustrated in Figures 1 and 2) the blade holder *a* is mounted in conjunction with the

45 handle *b* and guard *c* in such a manner that when reciprocated relatively to a strop *d* (Figures 3 and 4) which is threaded under

a roller *e* beneath the blade holder and over side rollers *f*, the roller *e* is alternately rotated in opposite directions, and this movement is utilized for swinging the blade holder through about 180° at the end of each stroke by connecting the roller and blade holder through a pair of toothed pinions as *g*, each pinion being arranged coaxially on the part on which it is mounted.

In one simple application of the invention to razors of this kind, the pinions *g* are arranged eccentrically, so that in the one direction of travel the turning moment exerted on the blade holder by the frictional engagement between the strop and roller (and consequently the pressure between the blade *h* and strop) is greater than in the other. By such a provision it is found that 65 much more satisfactory stropping of the blades is obtained than with the ordinary device. The action of the eccentric arrangement of pinions will be evident from Figures 3 and 4. Figures 3 shows the parts in the 70 relative positions which cause the maximum pressure to be exerted between the blade and strop. The direction of movement of the razor relatively to the strop is indicated by the arrow. In the next and opposite stroke 75 in which the direction is as shown by the arrow in Figure 4, the parts take up the position shown in that figure, and a less pressure is then set up between the blade and strop.

Having thus described my invention what I claim as new and desire to secure by Letters Patent is:—

In razor stropping devices, the combination comprising a strop, an oscillatory blade holder, a roller in frictional engagement with the strop, and eccentric pinions for transmitting motion from the roller to the blade holder for causing greater pressure to be exerted between blade and strop in one 90 stroke than in the next.

In testimony whereof I have signed my name to this specification.

ARTHUR JAMES POSTANS.
